OPERATING TABLE FOR PIGS

Joseph W. Duffy, Oldham, S. Dak.

Application December 6, 1955, Serial No. 551,296

10 Claims. (Cl. 119—103)

My invention relates to improvements in devices for holding small pigs while they are castrated and the primary object is to provide means into which the pig may be quickly placed, firmly held in convenient posture for this necessary operation and then quickly released after the operation is completed. In furtherance of this object of my invention I provide means of this nature which will hold the animal without injury thereto but so firmly that the operation may be carried out expeditiously, without danger of any damage to the animal.

Another object of my invention is to provide a little pig holder which is easy to use and operate by one man and which may be readily adjusted according to the size of the individual animal.

Still another object is to provide a device for this purpose which is simple and inexpensive in construction, durable and equipped with a folding stand so that the pig is held at a most convenient level for operation.

These and other more detailed and specific objects will be disclosed in the course of the following specification, reference being had to the accompanying drawings, in which—

Fig. 1 is a side elevation of my device in its operative position, holding a small pig in position for castration.

Fig. 2 is an end view.

Fig. 3 is a top plan view of the device alone.

Figs. 4 and 5 are, respectively, enlarged cross sectional detail views along the lines 4—4 and 5—5 in Fig. 1.

Referring now more particularly and by reference numerals to the drawing it will be seen that my invention consists of an upper member or section designated generally at 10 and a lower member or section 11, the latter having a base board 12 of rectilinear shape to which platform legs 13—14 are hinged at 15. These legs, conveniently made up from angle iron in the shape shown, may be folded toward each other and upwardly toward the underside of base board 12 as indicated in the dotted lines in Fig. 1 when the device is not in use but when swung apart and downwardly to vertical positions cannot swing beyond such positions due to location of the hinges 15 on the inner edges of the legs. A tie rod 16 hooked at its opposite ends 17 connects the legs when they are unfolded to hold the platform rigid when the device is in use.

The lower section 11 also includes, to form a trough or chute by side boards 18—19, the former being secured in place in a vertical edgewise position along one edge of the base board 12 while the latter is adjustable crosswise of the base board to vary the space between said side boards. For this purpose the side board 19 is provided with side brackets 20 secured in place and having outwardly turned feet 21 with notches 22 to accommodate bolts 23 extending upwardly from the base board 12 and fitted with wing nuts 24. By loosening the wing nuts 24 the side board 19 may be adjusted, by virtue of the notches 22, and then secured in place by re-tightening the wing nuts as will be readily appreciated. It might be noted at this point that the overall length of both of the sections 10—11 is greater

2

than that of the largest pig to be operated upon and the trough or chute formed by the base board 12 and side boards 18—19 provides a receptacle wherein the pig, designated at P in Figs. 1 and 2, may be placed in an upside down position.

A U-shaped end bracket 25 of strip iron or the like is secured to the base board 12 adjacent one end thereof and has upstanding side bars 26 which project well above the side boards 18—19 and are provided with vertically spaced apertures 27 for the selective reception of a hinge bolt 28 threaded at one end to receive a wing nut 29. Said end bracket also has a longitudinally projecting lug 30 apertured at 31 near its extremity for a purpose presently to appear.

The upper section 10 in the form of a swinging frame is made up of parallel side bars 32—33 of angle iron or the like and at one end these side bars are rigidly connected by a cross plate 34 in which are openings 35. At the opposite end a cross bar 36 rigidly joins the side bars 32—33 and in an intermediate location an adjustable cross plate 37 extends between the side bars. The latter slides along the inwardly turned flanges 38 of the side bars (Fig. 4) and is conveniently held against upward displacement by welding an inwardly turned bead 39 along the upper edges of the bars. Like the stationary cross plate 34 the movable plate 37 is provided with transversely spaced openings 40 and in addition plate 37 has a longitudinally extending tongue bar 41 and a tapering hold down plate 42 (Fig. 3).

Hinge bars 43 are welded or otherwise secured on edge to the cross bar 36 and extend therefrom longitudinally across the inner (or outer) sides of the side bars 26, said hinge bars being apertured (not shown) to pass the hinge bolt 28 to thus mount the upper section 10 for swinging movements upwardly and downwardly at its opposite end, with reference to the lower section or trough 11. One of said hinge bars 43, the one over the aforesaid lug 30, has an upwardly extending end 44 apertured at 45 and a retractile coil spring 46 is hooked at its ends into the apertures 31—45 to pull downwardly on the end of section 10 and thus tend to raise the opposite or free end of the section with respect to lower section 11.

The aforesaid tongue bar 41 has a series of longitudinally spaced apertures 47 and as best seen in Fig. 5 this bar extends endwise between the sides 48 of an inverted U-shaped element 49 secured at 50 to the cross bar 36. This is part of a latch assembly designated generally at 51 in Figs. 1—3 and includes a vertical latch plunger or keeper 52 slidably mounted downwardly through the top of element 49 and the cross bar 36 and adapted to selectively engage any of the aforesaid apertures 47. The plunger 52 is biased in a downward direction by an expansion coil spring 53 coiled around the plunger and braced between the top of element 49 and a collar 54 fixed to the plunger but the plunger may be raised against the bias of the spring and to clear the tongue bar 41 by a knob 55. Obviously the spacing between the cross plates 34—37 may be readily adjusted by manipulation of this latch assembly.

Completing the device is a flexible restraining or hold-down strap 56 connecting the side boards 18—19 and extending over the upper member 10 adjacent the end opposite the hinge therefor, said strap being provided with any conventional form of buckle 57 or analogous fastener 58.

In the use of the device the pig to be operated upon is laid in the trough or chute formed by the base and side boards 12, 18, 19 and the upper section 10 is then swung downwardly so that the pig's front and rear feet project upwardly through the openings 40 and 35 respectively in the cross plates 37 and 34. The width of the trough and the distance between the openings 35—40 are

both adjusted to suit the size of the pig as previously described. The strap 57 is then pulled taut and the pig is firmly held in a position in which the castrating operation may be readily and quickly performed, following which it is only necessary to release the strap and the spring 46 will swing the upper section 10 upwardly releasing the pig. The plate 42 holds the pig's head down and the pig is so firmly held that he cannot injure himself while the operation of putting the pig in place, fastening him there and then releasing him may be rapidly performed that one man may do the job with a minimum expenditure of time and effort. When not in use the device may be compactly stored away by folding the platform legs 13-14 as aforesaid. In addition to the adjustment of the side boards 18-19 and spacing between the leg openings 35-40 the entire upper section 10 may be raised or lowered to suit the size of the animal by placing the hinge bolt 28 in an appropriate pair of the apertures 27 and thus the device is fully adjustable to all sizes of animals and to their varying proportions.

It is understood that suitable modifications may be made in the structure as disclosed, provided such modifications come within the spirit and scope of the appended claims. Having now therefore fully illustrated and described my invention, what I claim to be new and desire to protect by Letters Patent is:

1. A device for holding an animal while it is operated upon, comprising a trough-like lower member of U-shaped cross section to receive the animal in an inverted position, a swinging upper section hinged at one end to said lower member and adapted when the animal is in place to be swung downwardly, said upper section having openings to receive the front and rear legs of the animal, and means for releasably holding the upper section downward to restrain the animal and hold it in said lower member.

2. A device of the character described for holding a small pig while it is castrated, comprising in combination, upper and lower sections and the latter being a U-shaped trough to receive the pig in an inverted position, the upper section having plate members apertured to receive and hold the feet of the pig, means for hinging the two sections together so that they may be opened to release the pig, and means for holding the sections together and thereby holding the pig in said trough.

3. A device of the character described for holding a small pig while it is castrated, comprising in combination, upper and lower sections and the latter being a U-shaped trough to receive the pig in an inverted position, the upper section having plate members apertured to receive and hold the feet of the pig, means for hinging the two sections together so that they may be opened to release the pig, means for holding the sections together and thereby holding the pig in said trough, and means for adjusting the spacing between the plate members according to the length of the pig.

4. A device of the character described for holding a small pig while it is castrated, comprising in combination, upper and lower sections and the latter being a U-shaped trough to receive the pig in an inverted position, the upper section having plate members apertured to receive and hold the feet of the pig, means for hinging the two sections together so that they may be opened to release the pig, means for holding the sections together and thereby holding the pig in said trough, the trough having a base board and spaced apart side boards thereon, and means adjustably mounting at least one of said side boards according to the width of the pig to be held.

5. In a pig holder for holding small pigs while they are castrated, a lower section having a base board and a pair of side boards mounted thereon and forming an open ended trough to hold a pig in an inverted position legs up, an upper section having side bars and cross members connecting the same, means at one end hinging the upper section to the lower section for upward and downward movement of the opposite end of the upper section

with respect to the lower, a pair of the cross members having spaced apart openings to receive the four legs of the pig, means for holding the upper section downwardly against the pig, and means for adjusting the hinge means to vary the position thereof relative to the lower section according to the vertical proportions of the pig.

6. In a pig holder for holding small pigs while they are castrated, a lower section having a base board and a pair of side boards mounted thereon and forming an open ended trough to hold a pig in an inverted position legs up, an upper section having side bars and cross members connecting the same, means at one end hinging the upper section to the lower section for upward and downward movement of the opposite end of the upper section with respect to the lower, a pair of the cross members having spaced apart openings to receive the four legs of the pig, means for holding the upper section downwardly against the pig, means for adjusting the hinge means to vary the position thereof relative to the lower according to the vertical proportions of the pig.

20 7. In a pig holder for holding small pigs while they are castrated, a lower section having a base board and a pair of side boards mounted thereon and forming an open ended trough to hold a pig in an inverted position legs up, an upper section having side bars and cross members connecting the same, means at one end hinging the upper section to the lower section for upward and downward movement of the opposite end of the upper section with respect to the lower, a pair of the cross members having spaced apart openings to receive the four legs of the pig, means for holding the upper section downwardly against the pig, means for adjusting the hinge means to vary the position thereof relative to the lower according to the vertical proportions of the pig, and means for adjusting one of the said side boards to vary the spacing thereof according to the width of the pig, and means for adjusting one of said cross members having said openings according to the length of the pig.

25 8. In a pig holder for holding small pigs while they are castrated, a lower section having a base board and a pair of side boards mounted thereon and forming an open ended trough to hold a pig in an inverted position legs up, an upper section having side bars and cross members connecting the same, means at one end hinging the upper section to the lower section for upward and downward movement of the opposite end of the upper section with respect to the lower, a pair of the cross members having spaced apart openings to receive the four legs of the pig, means for holding the upper section downwardly against the pig, means for adjusting the hinge means to vary the position thereof relative to the lower according to the vertical proportions of the pig, and a hold down plate between the side bars for holding the pig's head down.

30 9. In a pig holder for holding small pigs while they are castrated, a lower section having a base board and a pair of side boards mounted thereon and forming an open ended trough to hold a pig in an inverted position legs up, an upper section having side bars and cross members connecting the same, means at one end hinging the upper section to the lower section for upward and downward movement of the opposite end of the upper section with respect to the lower, a pair of the cross members having spaced apart openings to receive the four legs of the pig, means for holding the upper section downwardly against the pig, and a spring operatively arranged to normally swing the said upper section upwardly to release the pig.

35 10 11. In a pig holder for holding small pigs while they are castrated, a lower section having a base board and a pair of side boards mounted thereon and forming an open ended trough to hold a pig in an inverted position legs up, an upper section having side bars and cross members connecting the same, means at one end hinging the upper section to the lower section for upward and downward movement of the opposite end of the upper section with respect to the lower, a pair of the cross members having spaced apart openings to receive the four legs of the pig, means for holding the upper section downwardly against the pig, a tongue bar extending from one of said cross members having the said openings and means slidably mounting that cross member for movements lengthwise of the side bars, said tongue bar having a series of apertures, and a latch assembly having a spring biased and manually retractable plunger for selectively engaging said apertures and thereby adjusting the spacing between the cross members having the openings according to the length of the pig being held.

10. In a pig holder for holding small pigs while they are castrated, a lower section having a base board and a pair of side boards mounted thereon and forming an open ended trough to hold a pig in an inverted position legs up, an upper section having side bars and cross members connecting the same, means at one end hinging the upper section to the lower section for upward and downward movement of the opposite end of the upper section with respect to the lower, a pair of the cross members having spaced apart openings to receive the four legs 10

of the pig, means for holding the upper section downwardly against the pig, and means for adjusting the hinge means to vary the position thereof relative to the lower according to the vertical proportions of the pig, the said means for holding the upper section downward consisting of a buckled strap secured to the side boards and passing over the said upper section.
